UNITED STATES PATENT OFFICE.

DANIEL E. WILLIAMSON, OF DYERSBURG, TENNESSEE.

DESIGN FOR A BOTTLE.

46,271.

Specification for Design.

Patented Aug. 11, 1914.

Application filed May 3, 1913. Serial No. 765,384. Term of patent 7 years.

To all whom it may concern:

Be it known that I, DANIEL E. WILLIAMSON, a citizen of the United States, residing at Dyersburg, in the county of Dyer and State of Tennessee, have invented a new, original, and ornamental Design for Bottles, of which the following is a specification, reference being had to the accompanying drawing forming part thereof.

The figure is a perspective view of the bottle showing my new design.

I claim:

The ornamental design for a bottle, as shown.

DANIEL E. WILLIAMSON.

Witnesses:

WHIT THOMAS,

D. L. ANDERSON.
